UNITED STATES PATENT OFFICE.

SIMON W. WARDWELL, OF PROVIDENCE, RHODE ISLAND.

BRAIDING-MACHINE.

1,082,981.

Specification of Letters Patent. Patented Dec. 30, 1913.

Application filed January 28, 1911. Serial No. 605,266.

To all whom it may concern:

Be it known that I, SIMON W. WARDWELL, a citizen of the United States, residing at Providence, in the county of Providence and State of Rhode Island, have invented certain new and useful Improvements in Braiding-Machines, of which the following is a specification.

My invention relates to braiding-machines and particularly to the tension and drop-wire devices which act to control the delivery of the yarns from the supply-cops and effect the stopping of the machine when a yarn breaks, becomes exhausted or is hindered from delivering.

My invention is especially adapted for use on braiding-machines such as that shown and described in my Patent No. 1,032,870, dated July 16, 1912, in which the fabric is braided from a plurality of yarn supplies or cops arranged in two tiers and rotating in opposite directions about a common axis.

My invention consists of improvements in the devices for regulating the delivery of the yarns from the supply-cops and in the mechanism for causing the operation of the drop-wire which acts to stop the machine when a yarn breaks, the supply becomes exhausted or when the yarn becomes snarled or tangled or is otherwise prevented from delivering freely from the cop.

The invention is fully described in the following specification, illustrated by the accompanying drawings, in which:

Figure 1 is a side elevation of one of the carriers which support the upper supplies of yarn; Fig. 2, a plan view of the same; Fig. 3, an enlarged part-sectional plan view of the tension-mechanism for controlling the rotation of the cop-holder, taken on the line A—A of Fig. 1, looking in the direction indicated by the arrow *a*; Fig. 4, an enlarged side elevation of the tension-mechanism and drop-wire, part-sectional through the base of the cop-holder; Fig. 5, a detail view of the drop-wire; Fig. 6, a detail view of the tension-controlled lever for operating the drop-wire; Fig. 7, a detail view of the detent which controls the rotation of the cop-holder, showing it released from the rim of the brake-wheel.

Referring to Fig. 1, 2 is the shuttle or carrier which carries the upper yarn supply or cop *Y* and revolves it about the axis of the machine. The carrier 2 consists essentially

of a lenticularly shaped plate or deck 3, and a dependent keel or runner 4 which slides in a grooved race or track on the rim of one of the rotating turrets of the machine. The arrangement of the main elements of the braiding mechanism is shown and described in the pending application above referred to and need not be further described herein.

Mounted in a hub 5 on the deck of the carrier 2 is an upright spindle 6 on which the cop-holder 7 rotates. The tube or support *x* of the cop *Y*, represented by dash lines in Fig. 1, is slid on to the holder 7 and held rotatively therewith by any suitable means, such, for instance, as the blades or spurs 8 which indent the interior of the tube. The base of the cop-holder serves as a brake-wheel for controlling its rotation and consists of a cupped disk 9 formed with the downturned annular flanged rim 10. Referring to Fig. 3, the rim 10 is adapted to be engaged by a friction brake or detent 11 which controls the rotation of the cop-holder 7. The detent 11 consists of an axe-shaped plate 12, preferably formed of sheet-metal, with arcuate flanges or lugs 14 and 15 bent up from its curved side. The inner surface of the flange 14 corresponds to the peripheral face of the rim 10 and the outer surface of the flange 15 fits the inner face of the rim. The flanges 14 and 15 are spaced circumferentially apart around the rim 10 to allow the detent to be rocked as later described. The detent 11 is also formed with a slot 16 adapted to be engaged by a stud 17 secured in the deck of the carrier, see Fig. 4. The stud 17 acts as a pivot for the detent 11 and by swinging the latter thereon it can be caused to engage and grip the rim 10 to prevent the cop-holder from turning. When the detent is swung on its pivot in the direction indicated by the arrow *b*, Fig. 3, the flanges 14 and 15 dog on the rim 10 and grip the latter to apply a frictional braking force which acts to resist the rotation of the cop-holder. To release the cop-holder the detent 11 is moved in the opposite direction and the flanges 14 and 15 will then be removed from their gripping contact with the rim 10 as illustrated in Fig. 7.

The detent 11 is operated through the medium of a lever 18 connected therewith by the wire link 19 hooked into the ear 20. The lever 18 is pivoted on a wire 21 which

is mounted in bearings extending from an upright standard 22 fastened to the deck of the carrier. Preferably, the standard 22 is formed of sheet-metal with a foot 23 secured to the deck 3 by the screw 24. The main portion of the standard 22 extends upward to a point midway of the height of the supply-spindle 6 and is bowed forward in the arm 25 which is formed with a yarn-guide or eye 26 at its extremity, see Fig. 4. Two lugs or ears 27 are bent forward from the sides of the standard 22 and through these the wire 21 passes, see Fig. 3. The lever 18 is formed with ears 28 pivoted on the wire 21 outside of the ears 27. One end of the wire 21 is bent back in a loop 29 with its extremity terminating in the right-angled portion 30 which extends through an opening 31 in the standard 22. The end of this extension 30 is rounded off to facilitate its being pushed through the opening 31 and on its upper side is formed a notch 32 which engages the edge of the opening, see Fig. 4. In this manner the extension 30 serves as a latch or catch to hold the wire 21 in place after it has been put through the ears on the lever 18 and standard 22. To remove the wire from the ears it is only necessary to press down on the end of the extension 30 and snap it out of the opening 31 when the wire can be withdrawn.

The lever 18 has a depending arm 33 with a hole 34 into which is hooked the end of the link 19. At the extremity of this arm 33 is secured one end of a coiled spring 35 which has its opposite end fastened to a lever 36, see Fig. 3. The lever 36 is preferably constructed of wire with one end bent into a ring 37 which surrounds the hub 5 on the carrier deck and is seated in a peripheral groove 38. At 39 the lever takes the form of a "pigtail" to provide an eye into which is hooked the end of the spring 35. The end 40 of the lever 36 is adapted to engage notches or teeth 41 formed on a rib 42 on the under side of the carrier's deck 3, see Figs. 1 and 2. By adjusting the lever 36 along the notches 41 the tension of the spring 35 can be varied to regulate its effect on the lever 18.

One ear 28 of the lever 18 is formed with a finger 44 which reaches out to engage a lug 45 on a lever 46. The lever 46, like the lever 18, is pivoted on the wire 21 through the medium of two downturned ears 47 having holes for the wire, see Figs. 3 and 6. The main arm of the lever 46 terminates in a hook-shaped loop or guide 48 through which the yarn from the cop leads, as more fully described hereinafter. Extending upward from the main portion of the lever 46 is a curved arm 49 having a laterally projecting stud or pin 50 at its extremity. The pin 50 is adapted to engage a cam-groove 51 in the drop-wire 52 to regulate the position

of the latter according to the position of the lever 46 as now described: The drop-wire 52 is preferably formed of sheet-metal, shaped like an arrow-head with an extension 53 projecting downward from its point, as most clearly shown in Fig. 5. The upper shank 54 of the drop-wire is adapted to slide in a slotted bearing in the laterally extending lug 55 on the standard 22, see Figs. 3 and 4, and the extension 53 projects down through a hole in the foot 23 of the standard 22 and a corresponding opening in the deck of the carrier. Formed in the triangularly-shaped portion of the drop-wire is the cam-groove 51 having a curved portion 56 and two upwardly inclined branches 57 and 58. Normally the lever 46 is maintained by the tension of the yarn in the position illustrated in Fig. 4, with the pin 50 engaging the rounded face 59 of the cam-groove 51 to support the drop-wire 52 in its uppermost position. When the lever 46 is tilted either upward or downward, however, the pin 50 will travel in the branch 57 or branch 58 of the cam-groove and the drop-wire will be lowered in position in the manner and for the purpose as later described.

The operation of the whole device is as follows: The supply-cop Y is placed on the cop-holder 7 and the yarn y leading from its periphery is threaded through the guide-eye 26 and thence down through the guide-loop 48, see Fig. 1. From the loop 48 the yarn is drawn up again through the eye 26 and thence leads to the braiding point of the machine. The lever 36 is adjusted to regulate the tension on the spring 35 according to the strength of the yarn and the character of the fabric being produced. With a light yarn the lever is set to give a minimum resistance to the movement of the lever 18 so as not to strain or break the material, but with a heavier yarn greater resistance to delivery can be applied to produce a closely meshed fabric when so desired. With the parts in the position illustrated in Figs. 1 and 4 the spring 35 acts through the lever 18 and link 19 to force the detent 11 in the direction indicated by the arrow b, Fig. 3, to dog it on the rim 10 of the brake-wheel of the cop-holder 7. The yarn y being looped through the eye 48 on the lever 46 and drawn up to the braiding point suspends the lever 46 in position to bring its lug 45 against the under side of the finger 44 on the lever 18. With the lever 46 in this position the pin 50 on the arm 49 rests on the curved edge 59 of the cam-groove 51 and the drop-wire 52 is held thereby in its raised position. When the machine starts to operate its braiding action will create a draft on the yarn y and this first pull will cause the lever 46 to swing upward in the direction indicated by the arrow c, see Fig. 4. This lifting of the lever

46 acts through the lug 45 bearing on the under side of the finger 44 to tilt the lever 18 in the direction indicated by the arrow *d*. As the lever 18 is moved in this direction 5 against the action of its spring 35 it acts through the link 19 to move the detent 11 in the direction opposite to that indicated by the arrow *b*, Fig. 3. This releases the lugs 14 and 15 of the detent 11 from their dogging engagement with the rim 10 of the brake-wheel, as shown in Fig. 7, and the cop-holder is then free to rotate to deliver the yarn. Only a slight movement of the lever 18 is required to release the detent 11 10 from the rim of the brake-wheel and to effect this movement the lever 46 is only lifted to a correspondingly slight extent. During this slight movement the pin 50 on the arm 49 rides over the curved edge 59 15 of the cam-groove 51 and the position of the drop-wire 52 remains practically unchanged. That is to say, as the lever 46 swings up and down under slight variations in the tension of draft on the yarn the 20 pin 50 will ride back and forth around the curved portion of the cam-groove 51 without materially changing the position of the drop-wire. When, however, any abnormal resistance to delivery of the yarn is 25 encountered, as, for instance, by the catching or tangling of the yarn on the cop, the tension on the yarn will act to raise the lever 46 to a sufficient extent to carry the pin 50 into the branch 57 of the cam-groove 51. 30 As the pin 50 rides along this branch of the cam-groove the drop-wire 52 will drop bodily to project its lower end 53 below the deck of the carrier. The falling of the drop-wire brings its lower end into position to 35 engage the actuating devices of the stopping-mechanism which acts to arrest the operation of the machine. These latter devices are shown and described in my pending application, Serial No. 603,530, filed 40 January 19th, 1911, and need not here be explained as they form no part of the present invention. The drop-wire 52 also operates in the manner above described when a snarl or tangle occurs in the yarn as it leaves the 45 cop. Any abnormal bunch or knot in the yarn will be prevented from passing through the guide-eye 26 and the excessive tension on the yarn caused by such hindrance will act to lift the lever 46 to move the drop-wire 50 into its lowermost position.

When the yarn *y* breaks or the supply on the cop becomes exhausted the lever 46 is released and will drop under the action of gravity. As the lever 46 tilts downward 55 the pin 50 will ride out into the branch 58 of the cam-groove 51 and the drop-wire 52 will fall as before described. In this way the stopping of the machine is effected whenever the yarn fails to deliver properly from the supply-cop; either through breakage, ex-

haustion or other hindrance to unwinding due to snarling or catching of the yarn.

My invention provides a particularly effective device for controlling the rotation of the supply-holder to regulate the delivery of the yarn, and also a simple and positive means for actuating the stopping-mechanism of the machine when the yarn breaks, becomes tangled or is exhausted. The detent for the cop-holder is novel in arrangement 70 and operation and shows marked improvement over similar devices heretofore used. By dispensing with the pawl and ratchet arrangement usually employed for this purpose I eliminate the noise attendant upon 75 its operation and also reduce the friction and wear on the parts. The new device responds more sensitively to the variations in tension on the yarn and controls its delivery delicately but positively to prevent slackness 80 and overrunning. Furthermore, the extended engaging surfaces on the detent provide against wear, making the device practically indestructible and proof against getting out of order. There are no pawls or 85 ratchet teeth to become inoperative through wear and the improved arrangement provides against lint or dust interfering with the movement of the parts.

The drop-wire 52 is accurately and positively controlled by variations in the tension on the yarn and cannot chatter or jar into operative position from vibration of the machine. Neither can it be accidentally moved or displaced, but acts to stop the machine only upon the failure of the yarn.

Various modifications might be made in the form and arrangement of the parts without departing from the spirit and scope of the invention, therefore, without limiting 105 myself to the exact construction shown, what I claim is:—

1. The combination with a rotatable cop holder and a brake wheel rotatable therewith, of pivotally supported braking surfaces adapted to simultaneously engage opposite faces of a portion of said wheel when moving in one and the same direction, and means for shifting said braking surfaces to and from engagement with the brake wheel.

2. The combination with a rotatable cop holder and a flanged brake wheel rotatable therewith, of a pivotally mounted detent having braking surfaces positioned adjacent opposite faces of said rim, said braking surfaces being adapted to simultaneously engage the rim of the brake wheel while moving in one and the same direction and to release said rim by movement in the opposite direction, and means for rocking the detent.

3. The combination with a rotatable cop-holder, of a brake-wheel rotatable therewith, said brake-wheel having a flanged rim, a pivoted detent formed with braking surfaces adapted to engage the opposite sides of

4. In a supply-carrier for braiding-machines, the combination with a rotatable cop-holder for the supply-cop, of a brake-wheel rotatable therewith, said brake-wheel formed with a flanged rim, a detent formed with braking surfaces adapted to engage the opposite sides of the rim, means to normally hold said detent in position to resist the rotation of the brake-wheel, and means controlled by the tension on the yarn delivering from the supply-cop to release said detent. 75
5. In a supply-carrier for braiding-machines, the combination with a rotatable cop-holder, of means to regulate the rotation of the same, a lever to operate said means, said lever controlled by the tension on the yarn, and a drop-wire suspended on the lever and arranged to be operated thereby when the latter is moved abnormally either upon relief or excess of tension on the yarn. 80
6. In a supply-carrier for braiding or like machines, the combination with a rotatable cop-holder, of means to regulate the rotation of the same, a lever controlled by the tension on the yarn to actuate said means, and a drop-wire normally held in its raised position by said lever during the rotation of the cop-holder, but movable into its operative position by extreme movement of the lever under excess or relief of tension on the yarn. 90
7. In a supply-carrier for braiding or like machines, the combination with a rotatable cop-holder, of means to control the rotation of the same, a lever to operate said means, and a drop-wire suspended on said lever and movable into operative position by extreme movement of the lever in either direction. 100
8. In a supply-carrier for braiding or like machines, the combination with a rotatable cop-holder, of means to control the rotation of the same, devices controlled by the tension on the yarn to operate said means, and a drop-wire suspended by said devices in its raised position under normal tension on the yarn and moved into operative position under excess or relief of tension on the yarn. 110
9. The combination with a cop-holder, of means to control the delivery of the yarn from the supply-cop, devices controlled by the tension on the yarn to operate said means, and a drop-wire suspended by said devices in its raised position under normal tension on the yarn and moved into operative position under excess or relief of tension on the yarn. 120
10. The combination with a cop-holder, of means to control the delivery of the yarn from the supply-cop, a lever controlled by the tension on the yarn to operate said means, a drop-wire formed with cam-faces, and means on the lever adapted to engage the cam-faces to hold the drop-wire in its inoperative position under normal tension on the yarn and to move said drop-wire into operative position upon excess or relief of tension. 75
11. The combination with a rotatable cop-holder, of means to regulate the rotation of the same to control the delivery of the yarn, devices controlled by the tension on the yarn to operate said means, and a drop-wire connected with said devices to be moved thereby into operative position under excess or relief of tension on the yarn. 80
12. In a braiding or like machine, the combination with a drop-wire, of a lever controlled in position by the tension on the yarn, and means on said lever engaging the drop-wire to normally support it in inoperative position, said drop-wire connected with the lever to be moved positively thereby into operative position when the lever is rocked in either direction. 90
13. In a braiding or like machine, the combination with a lever controlled in position by the tension on the yarn, and a drop-wire suspended on said lever in its inoperative position under normal tension on the yarn and moved by the lever into its operative position when the lever is rocked in either direction under excess or relief of tension on the yarn. 100
14. In a supply-carrier, the combination with a lever controlled in position by the tension on the yarn, a drop-wire formed with cam-faces, and means on the lever to engage said cam-faces to hold the drop-wire in its inoperative position when the lever is in mid-position and to move the drop-wire into operative position when the lever is rocked in either direction. 105
15. In a supply-carrier, the combination with a pivoted lever, of a drop-wire formed with a cam-groove having a curved face and two oppositely extending angular faces, and means on the lever to engage the curved face of the cam-groove to hold the drop-wire in inoperative position and to engage the angular faces to move it into operative position. 115
16. The combination with a sliding drop-wire formed with a cam-groove having a curved portion and two branches extending therefrom in V-shape, of a lever having means to engage the curved portion of the groove to suspend the drop-wire in inoperative position, and to engage one or the other of the branches to lower the drop-wire into operative position when the lever is rocked in either direction. 120
17. The combination with a rotatable cop- 130

holder, of means to control the rotation of the same, a lever to operate said means, a second lever controlled by the tension on the yarn to operate the first lever, and a drop-wire suspended on the second lever and moved thereby into operative position when said lever is moved to its extreme position in either direction.

18. The combination with a rotatable cop-holder, of a detent to control the rotation of the same, a lever movable to operate said detent, a second lever controlled by the tension on the yarn to move the first lever, and a drop-wire connected with the second lever and adapted to be moved into operative position when said lever is moved beyond the extent necessary to move the first lever to operate the detent.

19. The combination with a rotatable cop-holder, of a detent to control the rotation of the same, a lever movable to operate said detent, a second lever controlled by the tension on the yarn to actuate the first lever, a drop-wire having cam-faces, and means on the second lever to engage the cam-faces to move the drop-wire into operative position when said lever is moved beyond the extent required to operate the detent.

20. The combination with a rotatable cop-holder, of a detent to control the rotation of the same, a lever to operate said detent, a second lever movable independently of the first lever but adapted to engage the latter to release the detent, and a drop-wire con-

nected with the second lever and carried thereby into operative position when said lever is moved beyond the extent required to operate the detent.

21. The combination with a rotatable cop-holder, of a detent to control the rotation of the same, a lever to operate said detent, a spring to normally maintain the detent in engagement with the cop-holder, a second lever adapted to operate the first lever to move the detent against the action of the spring, and a drop-wire connected to the second lever to be moved thereby into operative position when said lever is moved to its extreme position in either direction.

22. The combination with a standard having bearings, of a drop-wire 52 slidable in said bearings, and a lever 46 pivoted on said standard and connected with the drop-wire to suspend the latter in raised position and arranged to move the drop-wire to its lowermost position when the lever is rocked in either direction.

23. The combination with a vertically sliding drop-wire having a V-shaped cam-groove, of a lever having means adapted to engage said groove to raise and lower the drop-wire when the lever is rocked.

In testimony whereof I affix my signature in presence of two witnesses.

SIMON W. WARDWELL.
